UNITED STATES PATENT OFFICE.

HERMAN HAUG, OF NEW YORK, N. Y., ASSIGNOR TO GOLDING BROTHERS COMPANY, OF NEW YORK, N. Y., A CORPORATION OF NEW YORK.

DESIGN FOR A TEXTILE PANEL FOR MATTRESS COVERINGS.

Application filed October 25, 1928. Serial No. 28,636. Term of patent 3½ years.

To all whom it may concern:

Be it known that I, HERMAN HAUG, a citizen of the United States, residing at New York, in the county of New York and State of New York, have invented a new, original, and ornamental Design for Textile Panels for Mattress Coverings, of which the following is a specification, reference being had to the accompanying drawing, forming part thereof.

The figure is a face view showing one-half

of the complete design for a single panel or sheet of fabric for covering a mattress, identical panels bearing the illustrated design being used for the top and bottom of the completed mattress.

I claim:

The ornamental design for a textile panel for mattress coverings, as shown and described.

HERMAN HAUG.
